UNITED STATES PATENT OFFICE

2,249,441

SPRING MOTOR

William S. Sussman, New York, N. Y.

Application October 20, 1939, Serial No. 300,304

4 Claims. (Cl. 185—37)

This invention relates to new and useful improvements in spring motors and relates more particularly to an improved compact motor which, while so designed as to occupy a minimum amount of space, will nevertheless store a considerable amount of energy and will deliver a far greater amount of power than existing devices of this character.

One of the principal objects of the present invention is the provision of a small unitary prime mover adapted to be driven by a spring, the device being particularly adapted for driving a razor with a moving blade, the various operative parts being so arranged as to be entirely enclosed with a relatively small housing of such size as to be conveniently held in the hand of the user during the shaving operation.

Another object of the invention is the provision of a novel spring motor of small dimensions and having a novel arrangement of gears adapted to rotate a drive shaft at considerably higher speeds than presently known spring motors, and to operate without appreciable loss from friction.

Yet another object of the invention is the provision of a relatively high speed spring motor having a train of speed increasing gears housed within a small area and supported by a novel frame structure having a minimum of weight.

Whereas the present invention is illustrated as being used in connection with a mechanical shaver, it nevertheless will have a variety of uses such as for driving a small current generator in a flashlight and for many other uses.

A still further object of the invention is the provision of an improved spring motor with a train of gears all enclosed within a relatively small, elongated casing, such casing having associated therewith novel spring winding means free from any projecting parts such as cranks or the like.

Other objects of the invention will be hereafter specifically pointed out or will appear obvious as the specification proceeds.

In the drawing:

Fig. 1 is a longitudinal, vertical section taken through a preferred embodiment of the present invention;

Fig. 2 is a top plan view thereof;

Fig. 3 is a transverse, horizontal section taken on line 9—9 of Fig. 1;

Fig. 4 is a transverse, horizontal section taken on line 10—10 of Fig. 1;

Fig. 5 is a side elevation, partially in section, of one of the internal gear structures; and

Fig. 6 is a transverse vertical section taken through one of the support means for such internal gear structures.

The preferred embodiment of the invention includes a plurality of springs 110 contained within a cylindrical housing 111, such housing being provided with an integrally formed lower wall 112. The springs are also secured at their inner terminals 113 to a central vertical shaft 114 provided with a reduced portion 115 at its upper end, such reduced portion being journaled within a recess 116 formed in a main drive shaft 118.

A rotatable cylindrical housing 119 is formed integrally with such shaft 118, such housing enclosing the springs 110, the outer terminals 120 of which are secured to the inner wall of such housing. After the springs have been wound, the inner terminals thereof are held immovable, since the shaft 114 is itself immovable except when the springs are being wound. The outer terminals of the springs, however, impart rotative movement to the housing 119 carried by the drive shaft 118. A closure disc 123 is carried at the lower end of housing 119, the disc having a central aperture through which the lower end of shaft 114 passes, the shaft also passing through a central aperture 124 in the lower wall 112 of housing 111. At its lower end, the shaft is threaded as shown at 125 and this threaded portion is received in a threaded aperture 126 in an enlarged portion 127 of the base wall 128 of a base cap 129. This cap is carried on the exterior of housing 111 and it will be seen that as this cap is manually turned, the springs 110 are wound. Unwinding of the spring is prevented by means of a ratchet wheel 131 secured to the threaded portion 125 of shaft 114, such ratchet wheel being engaged by a conventional pawl 132 which is pivotally mounted on the lower surface of base wall 112.

The upper end of housing 111 is internally threaded as shown at 135 and is secured to an externally threaded portion of a base 136 of a frame structure which supports a train of gears, now to be described. A gear 140 having internal teeth 141 is keyed to the upper end of main drive shaft 118 by means of a set screw 143. This gear 140 is supported in an annular recessed portion 145 of frame structure 136 and the internal teeth of this gear engage a smaller gear 146 pivotally mounted at 147 on the lower surface of a stationary supporting structure 150, shown in detail in Fig. 6. This structure is desirably formed in one piece and includes an annular portion 151 having

a lower reduced annular portion 152, an internal annular seat 153 being formed substantially midway between the upper and lower ends of portion 151.

A plurality of these supporting structures 150 are placed one upon the other, the lower reduced portion 152 being received within the upper portion of the next upper supporting structure and resting upon seat 153. The reduced portion 152 of lowermost support 150 is received within a recess at the upper end of frame structure 136, the external diameter of annular portion 151 being the same as the external diameter of the upper extension of frame 136. The support is further formed with vertical apertures 155 on opposite sides thereof, elongated bolts 157 passing through the aligned apertures in the several supports 150, such bolts being threaded at their lower terminals and being positioned within threaded apertures 159 in base structure 136.

Support 150 is further formed with a lower base portion 156 having a central aperture 158. It will thus be apparent that as internal gear 140 mounted on main drive shaft 118 rotates, it imparts rotation to smaller gear 146, which gear meshes with a gear 165 mounted at the lower end of gear structure 162 (Fig. 5) having internal gear teeth 163, a hollow bushing 164 connecting small gear 165 with the main portion of structure 162. A central vertical shaft 167 freely journalled at its lower end in a central aperture 168 in the lowermost internal gear 140, passes through a central aperture 169 in gear structure 162, the latter being freely journalled on such shaft and accordingly such gear structure is driven more rapidly than gear 140, depending upon the ratio between such internal gear and gear 165.

The central aperture 158 in support 150 is of sufficient diameter to receive small gear 165 and the gear structure 162 is supported on the lower base portion 156 of support 150. The number of such speed increasing structures is dependent upon the speed desired, five being illustrated in the drawing. The uppermost internal gear structure, designated as 162', is received in a support 170 of greater depth than the other supports 150, a seat portion 171 near the upper end thereof receiving a journal member 173 having a central aperture 174 in a depressed portion 175 thereof. This aperture acts as the upper bearing for shaft 167 and such aperture has a reduced portion 176 which forms the lower bearing for a drive shaft 178. This shaft carries a gear 179 at the lower end thereof, such gear engaging a gear 180 pivotally mounted on a shaft 181 which is carried on the lower surface of a circular, upper frame member 182. This latter gear 180 is rotated by engagement with the teeth of upper internal gear structure 162' and an aperture 184 is formed in journal member 173 to receive this gear. Thus 60 rotational movement is transmitted from uppermost internal gear 162' to gear 180, and to gear 179 keyed to shaft 178.

Upper frame member 182 is secured in place by means of nuts 187 carried at the upper end of bolts 157 and this frame is provided with integrally formed, upwardly extending portions 188 which merge into threaded collar portion 189. These portions are curved, although such curvature is not apparent in Fig. 1.

A governor controls the speed of shaft 178, such governor being similar to that shown in the preferred embodiment and includes a fixed cup 191 mounted on the upper surface of frame 182 and a rotatable cup 192 having a collar 193

secured to shaft 178, the latter cup enclosing the former. Arms 195 are pivotally mounted at 196 within rotatable cup 192 as in the preferred embodiment. Likewise, a lever 197 centrally pivoted at 198 is urged against cup 192 by means of spring 199, the opposite end of such lever carrying a finger depressing portion 200 positioned within a suitable aperture in a tapered cylindrical gear housing 201.

10 This embodiment of the invention may be used for a variety of purposes and in the present instance it is shown as furnishing power for a mechanical razor having a head portion 204, supported by a nut 205 carried on the threaded portion of collar 189. In this instance, power for the moving cutter designated as 206 is furnished through the center shaft 178 and the shaving head is shown as being centrally positioned on the supporting nut 205.

20 In the event, however, that it is desired to connect a drive shaft to one or both ends of the moving element within the shaving head instead of to the center thereof, the power may be taken off at the side, as from the gear 180. In the ar-

25 rangement shown, however, the motor may also be used to operate a small power drill or screwdriver, or it may be used to operate a rotatable toothbrush. The foregoing are only a few of the many possible uses to which the motor may be put.

30 If the motor is to be run for any considerable length of time, the heat which may generate in the gear train may well be insulated from the outer housing 201 by filling the annular recess between the superimposed supporting members 150 and such housing with suitable insulating material such as mineral wool.

35 It will also be apparent that this embodiment of the invention may be modified considerably without departing from the spirit of the invention, as defined by the appended claims.

40 What I claim is:

1. A spring motor comprising a substantially cylindrical housing, a coiled spring positioned within the housing and being secured thereto 45 at its outer terminal, a winding shaft journalled in the center of the housing, the inner end of the spring being secured to said shaft, exteriorly disposed winding means secured to such shaft, a drive shaft carried by the housing, a driven shaft spaced from but in axial alignment with the drive shaft, and a plurality of trains of speed multiplying gears positioned in superimposed relationship between the two shafts to impart higher speed of rotation to the latter than the former, each train comprising an internal gear structure, the lowermost of said structure being carried by the drive shaft, a central driven gear carried by and spaced below each successive internal gear, and an idler gear between the internal gear and the driven gear carried by the next successive internal gear.

2. A spring motor comprising a substantially cylindrical housing formed with an end wall, a flat, coiled spring positioned within the housing and being secured thereto at its outer terminal, a winding shaft journalled in the center of the housing, the inner end of the spring being secured to said shaft, exteriorly disposed winding means including a winding cap secured to such shaft, a drive shaft formed on the end wall of the housing, a driven shaft spaced from but in axial alignment with the drive shaft, a governor carried by the driven shaft, and a plurality of trains of speed multiplying gears positioned in superimposed relationship between the two shafts to

impart higher speed of rotation to the latter than the former, each train comprising an internal driving gear structure and a central driven gear carried by and spaced below each internal gear, an idler gear between the internal gear and the driven gear carried by the next successive internal gear, the lowermost internal gear being carried by the drive shaft, the gears in the several trains having aligned apertures therein, and a supporting shaft passing through such apertures.

3. A spring motor comprising a substantially cylindrical housing, a flat, coiled spring positioned within the housing and being secured thereto at its outer terminal, a winding shaft journalled in the center of the housing, the inner end of the spring being secured to said shaft, and exteriorly disposed winding means secured to such shaft, a drive shaft carried by the housing, a driven shaft spaced from but in axial alignment with the drive shaft, and a plurality of frame structures positioned in superimposed relationship between the two shafts and a train of speed multiplying gears supported by each frame structure for imparting higher speed of rotation to the latter shaft than the former, each train comprising an internal driving gear structure, the lowermost of said structure being carried by the drive shaft, and a substantially small central driven gear formed integrally with and spaced below the internal gear, and an idler gear journalled on each

frame structure and being positioned between each internal gear and the driven gear.

4. A spring motor comprising a substantially cylindrical housing and a fixed end wall formed at its upper end, a coiled spring positioned within the housing and being secured thereto at its outer terminal, a winding shaft journalled in the center of the housing, the inner end of the spring being secured to said shaft, a frame structure including a portion extending below the housing, a spring pressed pawl carried thereon and a ratchet wheel carried on the shaft, a winding cap secured at the lower end of the shaft, a drive shaft secured to the upper wall of the housing, a driven shaft spaced from but in axial alignment with the drive shaft, a governor carried by the driven shaft, and a plurality of trains of speed multiplying gears positioned in superimposed relationship between the two shafts to impart higher speed of rotation to the latter than the former, each train comprising an internal driving gear structure and a central driven gear carried by and spaced below each internal gear, an idler gear between the internal gear and the driven gear carried by the next successive internal gear, the lowermost internal gear being carried by the drive shaft, the gears in the several trains having aligned apertures therein, and a supporting shaft passing through such apertures.

WILLIAM S. SUSSMAN.
